(57) **ABSTRACT**

A pulsed metal plasma thruster (MPT) cube has a plurality of thrusters, each having a first cathode electrode and a trigger electrode separated from the first electrode by an insulator sufficient to support an initiation plasma, and a porous anode electrode positioned a separation distance from the face of all of the cathode electrodes. The cathode electrode can be either the inner electrode or the outer electrode. A power supply delivers a high voltage pulse to the trigger electrode with respect to the cathode electrode sufficient to initiate a plasma on the surface of the insulator. The plasma transfers between the anode electrode and cathode electrode of selected thrusters, thereby generating a pulse of thrust.

SATELLITE METAL PLASMA THRUSTER AND CONTROL CIRCUIT

FIELD OF THE INVENTION

The present invention relates to a plasma thruster for use in a satellite. In particular, the invention relates to a metal plasma thruster (MPT) which develops pulsatile thrust through a series of plasma generation cycles.

BACKGROUND OF THE INVENTION

The next decade will see a dramatic increase in the number of small satellites launched into Low Earth Orbit (LEO). These satellites range in mass from <1kg pico- and femto-satellites up to nano-satellites (1 kg to 10 kg) and micro-satellites (10 kg to 100 kg). The small mass of pico- and femto-satellites makes it difficult to provide useful in-space propulsion, as the mass of fuel needed for even small maneuvers would exceed the satellite mass. Larger satellites such as small satellites (100 kg to 500 kg) and still larger satellites have available a wide range of well tested, in-space propulsion systems such as chemical rockets (hydrazine fueled, manufactured by Busek), electrothermal arcjets (manufactured by Aerojet) or electric propulsion thrusters such as Hall thrusters and Ion engines (manufactured by Busek).

As many as several thousands of the nano- and micro-satellites are expected to populate LEO, serving functions from imaging of the earth for crop and disaster management to provision of internet services. These satellites require onboard propulsion for station keeping, attitude adjustment or orbital maneuvers. Electric propulsion is more fuel efficient than chemical propulsion, but new forms of electric propulsion are required to meet the low-mass and size constraints imposed by these satellites. Scaling existing electric propulsion engines such as Xe ion engines and Hall thrusters down to ~1 W to 10 W power levels is not practical. The unavoidable overhead mass of propellant storage tank, flow controls and plumbing in Xe ion engines and the increasing magnetic field with decreasing size in Hall thrusters makes their overall efficiency unacceptably low at these power levels.

One type of prior art plasma thruster is known as a PTFE Pulsed Plasma Thruster (PPT), which uses PTFE propellants in a configuration where the PTFE is positioned between two electrodes, a plasma is generated across the electrodes, and the PTFE is consumed in a series of high velocity plasma ejections which generate the desired thrust. A drawback to PTFE is that because the plasma is developed across electrically insulating PTFE, a large initiation voltage needs to be developed, and accordingly, the typical energy storage device is a high voltage capacitor that is charged to about 2 kV for each discharge cycle. In addition, the prior art PPT also requires a spark plug trigger to initiate the discharge. This spark plug trigger is charged to an even higher voltage, typically 5 kV to 10 kV, since the plasma is initiated over insulating PTFE propellant. The PPT thus uses high voltage components that require larger insulation gaps in the thruster assembly than would be required in an alternative lower voltage thruster which forms a plasma over a previously metallized film surface. The plasma from the PPT that provides thrust is composed of ions of carbon and fluorine. As such, the exhaust speed of this carbon/fluorine plasma is in the range of 5 km/s to 6 km/s, a comparatively low exhaust speed in contrast to other alternative thruster types which may range from 8 km/s to 20 km/s. The amount of

propellant required to accomplish a mission in space depends exponentially on the exhaust speed. Hence the comparatively low exhaust speed of the prior art PPT makes it a less desirable option.

Another type of thruster is a Vacuum Arc Thruster (VAT), which utilizes two electrodes in combination with an insulator coated with a very thin layer of deposition metal. The prior art VAT relies on energy stored in an inductor to produce the discharge plasma across the insulator, which results in the vaporization of metal and associated thrust. In the prior art VAT, an inductor is first charged through a switch to a first current threshold, which triggers the opening of the switch. When the switch is opened, the inductive energy is released, and an inductive voltage peak LdI/dt is produced, which initiates a plasma arc by first forming microplasmas across the microgaps formed by breaks in a thin conductive surface applied to the surface of an insulating separator positioned between the anode electrode and the cathode electrode. The plurality of initial microplasma sites assists in the initiation of the main plasma discharge. These micro-plasmas expand into the surrounding space and allow current to flow directly from the cathode to the anode along a lower resistance plasma discharge path (100's of mQ) than the initial thin film surface discharge path. The current that was flowing in the solid-state switch (for ~100 μ s to 500 μ s) before it was actively opened is fully switched to the vacuum arc load. Typical currents of ~100 A (for ~100 μ s to 500 μ s) are conducted with voltages of ~25 V to 30 V. Consequently, most of the magnetic energy stored in the inductor is deposited into the plasma pulse. A shortcoming of the VAT is the energy that is dissipated by the storage inductor and I^2R switch losses during the charging cycle. During this phase of developing energy stored in the inductor, the current flows through the inductor and the switch, but not in the arc discharge, as the voltage necessary to trigger the arc is generated only after the switch is opened. The inductor and the switch are both dissipative elements, so a portion of the energy in each cycle is dissipated as heat in these elements. Another shortcoming of the VAT is re-deposition of ejected metal from the cathode onto the insulating layer. One prior art VAT geometry relies on the placement of the anode and cathode together as parallel electrode plates, with the electrode plates extending beyond the insulator in non-thrust directions to prevent plasma formation in those areas. However, devices of this construction have a shorter than desirable cycle lifetime before re-deposition of a film in excess of what the inductor can vaporize at arc initiation. This ultimately limits the number of cycles of thrust the device can provide. Additionally, the consumption of the cathode electrode creates an asymmetry which shortens the number of usable discharges. Another prior art VAT geometry has a series of ring electrodes acting as anode/cathode pairs. This configuration requires redirecting the ions which are ejected perpendicular to the desired thrust direction, using the energy storage inductor as a combined energy storage and particle redirection structure, with the discharged ions guided by the axial magnetic field of the storage inductor and an external cathode, as described in U.S. Pat. No. 7,518,085 by the present applicant.

From a different field of prior art plasma thrusters is a Field Emission Electric Propulsion (FEEP) device, which emits ions in continuous streams from needle electrodes. The ions in a FEEP are supplied from a non-toxic liquid salt that is stored in passive tanks. This liquid is wicked along the electrode tips by capillary action. The salt may consist of both positive and negative ions with masses ranging from a few hundred to several hundred Daltons. By periodically

varying the polarity of the extraction potentials, positive and negative ions are extracted, thereby forming a charge neutral ion beam that exits the thruster. If only positive ions are extracted from the ion containing salt, a separate electron gun is required to neutralize the beam as otherwise expulsion of ions would charge the spacecraft up to a negative potential that in turn draws the ions back to the spacecraft, resulting in no thrust. The classical Focused Ion Beam (FIB) sources on which these FEEP thrusters are based use ~ 10 kV potentials across gaps of ~ 1 mm. In the case of the FEEP thrusters, the potential is lower (~ 1 kV) hence the gaps must be smaller (~ 100 μ m). The tight gaps between electrodes and high electric fields in the device pose challenges for fabrication of millions of emitters that operate reliably in unison, which results in reliability and manufacturability problems.

It is desired to provide an improved plasma thruster operative with higher exhaust velocity ions than in the PPT, with improved reliability and lifetime over the prior art VAT, and with components that are simpler to fabricate and more reliable in operation than the FEEP thruster.

OBJECTS OF THE INVENTION

A first object of the invention is a metal plasma thruster comprising:

- a porous anode;
- an inner trigger electrode;
- an inner insulator surrounding the inner trigger electrode and having a conductive coating, the conductive coating having micro-gaps, the conductive coating in contact with the inner trigger electrode;
- a metal cathode surrounding the inner insulator, the metal cathode having an extent and a face exposed to the anode;
- an outer insulator surrounding the metal cathode, the outer insulator having a conductive coating, the conductive coating having micro-gaps;
- an outer trigger electrode in contact with the conductive coating of the outer insulator;
- the metal cathode having a terminus and a face exposed to the porous anode;
- the inner insulator having an extent from the terminus which is less than the extent of the metal cathode;
- the outer insulator conductive coating having an extent starting from the cathode face which is less than the extent of the metal cathode;
- where the metal cathode face is square, rectangular, or circular;
- and the outer trigger electrode has one or more conductive regions for forming an initiation plasma with the metal cathode.

A second object of the invention is a metal plasma thruster comprising:

- a porous anode;
- a metal cathode;
- an outer insulator surrounding the metal cathode, the outer insulator having a conductive coating, the conductive coating having micro-gaps;
- an outer trigger electrode in contact with the conductive coating of the outer insulator;
- the metal cathode having a terminus and a face exposed to the porous anode;
- where the metal cathode face is square, rectangular, or circular;
- and the outer trigger electrode has one or more conductive regions for forming an initiation plasma with the metal cathode.

A third object of the invention is a metal plasma thruster comprising:

- an inner trigger electrode;
- an inner insulator surrounding the inner trigger electrode;
- 5 a cathode electrode having a face, the cathode electrode surrounding the inner insulator;
- an outer insulator surrounding the cathode electrode;
- an outer trigger electrode surrounding the outer insulator and having a face which is substantially contiguous with the central cathode electrode face and the outer insulator, a surface of the outer insulator providing a plasma formation surface to the face of the cathode electrode;
- 10 at least one of the inner insulator or the outer insulator having a first surface co-planar to the central cathode electrode face, and having a second surface which is proximal to the first surface and obscured from re-deposition of material ejected from the central cathode face;
- 15 a porous anode positioned opposite the cathode face.
- A fourth object of the invention is a metal plasma thruster comprising:
- 20 an inner trigger electrode having a face;
- an inner insulator surrounding the inner trigger electrode;
- a cathode electrode surrounding the inner insulator;
- an outer insulator surrounding the cathode electrode;
- an outer trigger electrode having a face;
- 25 at least one of the inner insulator or the outer insulator having a first surface which is parallel to the cathode electrode face, the inner insulator or the outer insulator having at least one second surface which is obscured from re-deposition of material ejected from the cathode electrode face;
- 30 a porous anode electrode positioned opposite the cathode electrode face.

A fifth object of the invention is a power supply for a metal plasma thruster (MPT) having an anode output, a reference output, and a trigger output, the power supply comprising:

- 35 a first capacitor coupled to a source of charge, the capacitor connected to the reference output and having a voltage terminal;
- an inductor positioned between the anode output and capacitor voltage terminal;
- 40 a switch element positioned between the anode output and reference output;
- a second capacitor placed between the anode output and the trigger output;
- 45 a controller which keeps the switch open during a charge interval until the first capacitor reaches a threshold voltage, or alternatively holds the first capacitor at a threshold voltage until a thrust event is required, the controller thereafter closing the switch for an interval sufficient for the inductor to develop the requisite current to subsequently form a trigger arc upon the switch opening, the trigger arc formed between a trigger electrode connected to the trigger output and a cathode connected to the reference output, the trigger arc thereafter causing a plasma formation between a cathode connected to the reference output and an anode connected to the anode output.

SUMMARY OF THE INVENTION

In one example of the invention, a metal plasma thruster (MPT) has an inner trigger electrode surrounded by an inner insulating trigger plasma initiator, the inner insulating initiator comprising an insulator having a conductive surface with micro-gaps, the inner insulating initiator surrounded by

a cathode electrode, the cathode electrode surrounded by an outer insulating initiator comprising an insulator having a conductive surface with micro-gaps, the outer insulating initiator surrounded by an outer trigger electrode. In one example configuration, a porous anode electrode is positioned a separation distance from the face of the cathode.

In another example configuration, a thruster has a cathode electrode with a face which initiates a plasma over a treated surface of an inner insulator and inner trigger electrode, or over a treated surface of an outer insulator and outer trigger electrode. The inner trigger electrode or outer trigger electrode initiate a plasma over the inner insulator or outer insulator, respectively. Once a plasma is initiated near the face of the cathode, a significantly longer thrust cycle begins where a plasma is initiated between the cathode face and a porous anode, and the metal ions of the plasma are hydro-dynamically accelerated and pass through the porous anode, generating a thrust cycle. A plurality of thrusters may be positioned on a cube for use in a satellite, providing three axis control of application of thrust.

Compared to the prior art PTFE PPT which requires a high voltage trigger and ejects low velocity propellant, or the VAT which requires a storage inductor which includes a charging cycle during which time approximately 25% to 50% of the stored energy is lost, the inventors have found the metal plasma of the present invention to be far more energy efficient. The MPT charges the inductor for a very short time (<100 μ s) when compared to the arc discharge time (~3 ms to 6 ms). This means that less than 5% of the stored charge in the MPT storage capacitor is discharged up to the point that the switch is opened, allowing >95% of the charge to flow in the arc discharge plasma, contributing to thrust. By contrast, the VAT requires the current prior to discharge to be at its maximum value before its switch is opened, which results in <50% of the stored charge flowing into the arc.

In another example of the invention, a power supply has a ground reference, a trigger output, and an anode output for connection to a cathode, trigger, and anode, respectively of a metal plasma thruster. The power supply has a controller which provides a variable storage capacitor charge time and a variable inductive switch time. The power supply and controller are operative to generate thrust events from the metal plasma thruster, the power supply having a first storage capacitor having one terminal connected to a charging source and the other terminal connected to the ground reference. An inductor is positioned between the first capacitor charging source terminal and the anode output. A second capacitor is coupled from the anode output to the trigger output of the power supply. The trigger electrode of the plasma thruster is in close proximity to the cathode electrode sufficient to initiate a plasma arc. The anode output and reference output are periodically connected together by a switch element which is actuated by the controller. The controller is operative to keep the switch element open until the first capacitor charges to a threshold voltage and/or a thrust cycle event is requested, thereafter closing the switch for an interval of time sufficient for the inductor to charge enough current through the inductor such that upon opening the switch, the Ldi/dt voltage spike initiates an arc between the MPT trigger electrode and cathode electrode upon the opening of the switch. The switch remains open for the duration of a thrust cycle, during which time the plasma transfers from between the trigger electrode and cathode electrode to between the cathode electrode and anode electrode, thereby generating thrust through the thrust cycle until the current is insufficient to maintain the plasma, at which time the first capacitor charge, switch closure, switch open-

ing, and thrust cycle repeats. Each cycle results in the generation of a pulsatile thrust event.

DETAILED DESCRIPTION OF THE INVENTION

FIG. 1A shows a front view of a first configuration for a metal plasma thruster (MPT) where a central trigger electrode 110 is separated from a cathode face 108 by an annular insulator 101 over which an initiation plasma is formed. The insulator 101 may be formed from glass, ceramics, Alumina (aluminum oxide), or any insulator with a high melting point. In an example of the invention, cured epoxy resins and cured epoxy laminates (such as the glass-reinforced epoxy laminate FR4) may be used to form an insulator with a surface providing conductive micro-gaps between trigger electrode and cathode for formation of plasma-initiating

sparks over the many micro-gaps. FIG. 1B shows an alternative circumferential trigger configuration where a central cathode face 113 is separated by an outer circumferential trigger electrode 109 with insulator 111 positioned inside the radial extent of the trigger electrode 109. Axial trigger configuration FIG. 1A is a front view best understood in combination with side section view FIG. 3, and circumferential trigger configuration FIG. 1B is best understood in combination with side section view FIG. 4.

The cathode 108 of FIG. 1A or 113 of FIG. 1B may be formed of any material, preferably a metal which provides a comparatively high erosion rate during operation, indicating a comparatively high mass flow rate, in combination with a high exhaust speed. Suitable materials include any of the elements: Lithium (Li), Carbon (C), Magnesium (Mg), Aluminum (Al), Titanium (Ti), Chromium (Cr), Niobium (Nb), Molybdenum (Mo), Tantalum (Ta), Tungsten (W), Platinum (Pt), or Uranium (U). The below table identifies each cathode element with atomic mass unit (AMU), maximum metallic ion velocity in m/s, and specific impulse I_{SP} (change in momentum per unit of propellant consumed).

TABLE 2

1 Metal	2 AMU	3 speed, m/s	4 ISP (s)
C	12	17403	1774

Pt	195.08	8105	826
U	238.03	11339	1156

The propellants listed in Table 1 are not exclusive, as any conducting solid element or alloy may be used as an electrode material in the MPT, ranging from Lithium at the low mass end to depleted Uranium or higher at the upper mass end. A comprehensive list of suitable cathode metals for the present invention, sorted by melting point, includes: Magnesium, Aluminum, Radium, Barium, Strontium, Cerium, Europium, Ytterbium, Calcium, Lanthanum, Praseodymium, Silver, Neodymium, Actinium, Gold, Samarium, Copper, Promethium, Uranium, Manganese, Beryllium, Gadolinium, Terbium, Dysprosium, Nickel, Holmium, Cobalt, Erbium, Yttrium, Iron, Scandium, Thulium, Palladium, Protactinium, Lutetium, Titanium, Thorium, Platinum, Zirconium, Chromium, Vanadium, Rhodium, Hafnium, Technetium, Ruthenium, Iridium, Niobium, Molybdenum, Tantalum, Osmium, Rhenium, Tungsten, and Carbon. These metals may be referred to as “tier 1” metals, which may be present in the cathode in elemental form, or as alloys of other metals.

Alternative metals with a lower melting point which could be used as a cathode in the present MPT include: Francium, Cesium, Gallium, Rubidium, Potassium, Sodium, Indium, Lithium, Tin, Polonium, Bismuth, Thallium, Cadmium, Lead, and Zinc. These materials may be referred to as “tier 2” metals, which may be present in elemental form, or as alloys of other metals. In the scope of the present invention, the above “tier 1” and “tier 2” metals listed above are understood to be suitable for use as cathode material for the MPT individually, or alloyed with other metals, for use in forming the MPT cathode in the present invention. Although

the metals are sorted by melting point, this is not intended to imply a preferred order for use in the cathode of the MPT.

The MPT offers a broad range of I_{SP} from 800 s to 2400 s, whereas PTFE (Teflon®) of the prior art PPT is limited to a narrower range of values of roughly 525 s to 600 s.

The anode 114 for axial trigger thruster of FIG. 1A or circumferential trigger thruster of FIG. 1B is a conductive electrode positioned a separation distance from the cathode (108 or 113) face, and the anode 114 has greater than 80% porosity to allow passage of accelerated metal ions. The anode 114 may have any shape including a screen or an annular ring or a torus with a diameter which is equal to or greater than the diameter of the cathode 108 of FIG. 1A or trigger electrode 109 of FIG. 1B. The anode may be formed from any conductive material, refractory metal, or a stainless steel alloy such as an alloy containing at least steel and chromium, and with the largest practical porosity, so that the metal ions are accelerated away from the cathode but propagate through the porous anode.

FIG. 1A-1 shows a section view of FIG. 1A MPT where the trigger electrode 110 generates a pulsatile voltage which is applied between the trigger electrode 110 and cathode 108 and which exceeds a breakdown voltage across the insulator 101. In the MPT of FIG. 1A-1, the high voltage pulse is applied between the trigger lead 102 and the grounded cathode lead 104 using the power supply 201 of FIG. 2.

FIG. 2 shows a power supply 201 for use with any of the plasma thruster 207 configurations previously described, including the axial trigger thruster 207A or circumferential trigger thruster 207B. A third thruster 207C is of dual trigger geometry with both an inner trigger and outer trigger electrode, and positioned at different axial extents, as will be described for FIG. 10A, 10, AND 10C. A power supply 202 charges an energy storage capacitor C1 206. A controller 203 determines the rate of charge, how often to discharge thrust, when to close switch 208, and for how long to close switch 208 according to requested thrust, material consumption, trigger requirements, and other input parameters. Switch 208 is normally off and may be an insulated gate bipolar transistor (IGBT), a field effect transistor (FET), bipolar transistor, or any other controllable switch element capable of withstanding high voltages (in excess of 1 kV) and 100 A currents, the switch 208 having low switch-on resistance (<30 mΩ), and a fast (<500 ns) switching time. During the time the switch 208 is off, trigger 102 and grounded cathode 104 are equipotential to each other. When the voltage across C1 206 reaches a threshold voltage determined by controller 203, and when the controller 203 has a request for a thrust event, a trigger voltage V_g is delivered as a short pulse of duration T1 (of FIG. 5) to switch 208, which closes and causes a current to flow through L1 for a duration of time T1 sufficient to generate an initiation plasma when switch 208 is opened at the end of T1, which causes a positive voltage spike to be developed at switch 208, which is coupled through trigger capacitor C2 210 to trigger lead 102. The resulting trigger plasma formed between the trigger electrode 110/109 of FIGS. 1A and 1B and cathode electrode 108/113 of FIGS. 1A and 1B is the result of current flowing through the circuit formed by C1, L1, C2, trigger lead 102 and cathode lead 104. The interval T1 for which the gate V_g enables the switch 208 is selected to be sufficient only for plasma initiation, after which the plasma thrust interval T2 (of FIG. 5) begins, during which time the main plasma from cathode 108/113 (associated with cathode lead 104) to anode 114 (associated with anode lead 106) develops, through the circuit C1 206, L1 204, anode lead 106 and cathode lead 104. To minimize trigger energy losses, inductor L1 204 and

the interval T1 are selected to be the smallest possible values sufficient to generate a sufficiently high voltage (Ldi/dt) to trigger micro-discharge plasmas across the face of the metallized insulator (region 301 of FIG. 3 or region 401 of FIG. 4 with surface profile 402 and central axis 403) and thereby to facilitate arc breakdown between the cathode 104 and anode 106.

The first capacitor C1 206 is charged (generally up to 30V-100 V or other suitable voltage) by a DC current directly from power supply 202, such as from a spacecraft solar source, or with a charge rate regulated by controller 203. Initially both the switch (IGBT or MOSFET 208) and the trigger plasma path from trigger electrode 110 to cathode 108 across insulator 101 (of FIG. 1), or trigger electrode 109 to cathode 113 across insulator 111 are open and the vacuum gap between the cathode (108 or 113, respectively) and anode 114 also ensures that no current flows back to the power supply ground across that gap. When C1 206 is fully charged, a trigger signal Vg is sent by controller 203 to the control input of the switch to close the switch 208 and current flows from C1 206 through the coil L1 204, the switch 208 and returns to the capacitor ground, building increasing current in L1 204 until such current allows generation of a sufficiently high Ldi/dt voltage when the switch T1 208 is opened, to generate a trigger electrode arc. In one example, after 30 μ s to 100 μ s, the switch 208 is opened by control input Vg returning to 0 V, and the voltage (Ldi/dt) developed by L1 204 is delivered through C2 210 to the trigger electrode to initiate the plasma between the trigger electrode and cathode electrode across the insulator gap.

Inductor 204 has an inductance value which is just high enough to generate an adequate breakdown voltage (such as in the range 200 V to 1000 V) across the insulator gap between cathode 108/113 and trigger electrode 110/109. Hence this inductor 204 may be small and low mass, as opposed to the inductor in the prior art VAT which must be of high enough value to store the required arc energy applied between anode and cathode of that configuration. In the MPT, the inductor is not the primary energy source for the arc and serves only to provide the Ldi/dt voltage spike necessary to trigger the arc. The charge and energy to the arc are provided mainly by the storage capacitor C1.

FIG. 5 shows waveforms of operation for the Metal Plasma Thruster. An energy storage capacitor (C1 206 of FIG. 2) is charged by an external power source developing a voltage Vc 504. When the capacitor voltage reaches a threshold voltage 502 and upon command from the controller 203 of FIG. 2, the switch 208 is triggered by Vg 508 during T1, which causes the switch 208 to close. The trigger T1 interval removes a small amount of charge from the capacitor, which is used to initiate a trigger plasma such as 120 shown in FIG. 1A-1, or analogously across the insulator of region 301 of FIG. 3 or the insulator of region 401 of FIG. 4. Subsequent to the trigger T1 interval is the plasma thrust interval T2 of FIG. 5, where the plasma spreads between the cathode face and the anode 114 of FIG. 3 or 4, shown as 122 of FIG. 1A-2. During T2, the stored charge in the capacitor is depleted by plasma generation until the capacitor voltage or arc current drops below a voltage level which no longer supports the plasma. The cycle repeats at the next trigger Vg event, and the repetition period T3 is limited by the current provided to the capacitor by the external charging circuit.

FIG. 6 shows the current and voltage during the main cathode to anode arc period lasting an example thrust interval of 3 ms, corresponding to interval T2 of FIG. 5. Waveform 602 shows example anode electrode current, and

waveform 604 shows example anode electrode voltage with respect to the grounded cathode, for an example fixed arc resistance of 30 m Ω and an arc sheath potential drop of 19 V. One component of applied voltage developing a plasma 5 is the sheath potential plus an Ohmic voltage drop across the arc. The sheath potential is a well-known phenomenon in arc discharges, where ions from the main discharge plasma in the anode-cathode gap return across a cathode sheath, gaining energy, ~10 eV to 15 eV for each singly charged ion, and 10 heat the cathode locally in several spots to support field enhanced thermionic emission of the electrons needed to carry the arc current from cathode to anode. Those current carrying electrons cross another thin sheath at the anode, gaining energy (~10 eV) and deposit that energy as heat into 15 the anode. The sum of the cathode and anode sheath potentials is 19 V in this example. At the peak current of 230 A, the Ohmic drop is $230 A * 30 m\Omega \approx 7$ V. With the 19 V sheath drop added, the total voltage of the arc (between cathode and anode) at peak current is 26 V. This terminal 20 voltage between cathode and anode is called the burning voltage of the arc.

FIG. 7 shows the waveforms for an interval of time from 701 to 703 corresponding to the switch transitioning from T1 (Vg on) to T2 (Vg off), where the plot 704 shows capacitor 25 C1 charged, and the switch 208 closed until time 701, during which first interval the current through C1 206, L1 204, and switch 208 ramps as I_{L1} 702 until time 701 when the switch 30 opens and the trigger plasma initiates. During the interval from 701 to 703, the current path transitions to C1, L1, C210 and trigger electrode 102, followed by the current flowing 35 through anode 106 to cathode 104. At time 703, the plasma has spread from cathode 108/113 to anode 114, and the current continues to ramp from time 703 onwards as the plasma grows between the cathode and anode (electrode), 40 resulting in an effectively decreasing resistance across the plasma until the stored energy in capacitor 206 no longer supports a plasma. Plot I_{L1} 702 shows a linear ramp up to about 70 A at time 701 during the first 90 μ s of an example 45 T1 when the switch is closed, followed by a slight dip and a sinusoidal increase thereafter. Anode current plot 702 is for the example of FIG. 2, with example component values C1=10.5 mF, L1=70 pH and a total loop resistance (of the capacitor, coil and switch in its closed state) of 40 m Ω .

FIG. 8 shows the waveforms for a segment in time which includes the trigger interval, shown starting at ~45 μ s when the switch 208 opens at the end of T1 interval 807. As the switch opens, its internal resistance rapidly increases, causing the current in the switch 208 to decay rapidly. The interruption of current through switch 208 causes the voltage applied to the trigger electrode Vtrig 806 to rapidly increase, causing a plasma to develop at the trigger electrode. At that moment, trigger electrode current 804 begins to flow and generates more trigger plasma. As the trigger plasma fills the gap between the cathode and anode the plasma current path 55 transitions from between cathode and trigger to between cathode and anode, and the trigger capacitor now drives current in the opposite direction and the trigger current 804 reverses polarity. The inductor current I_{L1} 802 changes slope during the trigger plasma interval from 45 μ s to 55 μ s as the 60 current starts to decay due to the rapidly increasing resistance in switch 208. The change in current contributes to the Ldi/dt voltage and as that voltage increases, current flowing through the switch 208 is diverted to the trigger electrode 102 for forming the initial trigger arc to the cathode. When 65 the switch is opened (at ~43 μ s in the instant FIG. 8 example), the dip in current I_L 802 in coil L1 generates a voltage Ldi/dt V_{TRIG} 806 at the coil output node. The initial

11

fast (~200 ns) voltage spike of 120 V passes through the blocking capacitor **C2 210**, which is selected to offer low impedance (<1 Ω) to a fast (<1 μ s) rise time pulse and creates a flashover plasma (**120** of FIG. 1A-1) across the metallized (~10 Ω to 1 k Ω) insulator surface (region **301** of FIG. 2 or region **401** of FIG. 4) between the trigger electrode (**110** of FIG. 3 or **109** of FIG. 4, respectively) and the cathode (**108** of FIG. 3 or **113** of FIG. 4, respectively). An example trigger current from the trigger electrode to cathode electrode has a magnitude of 45 A (which implies a flashover resistance of approximately 2.7 Ω) and creates sufficient plasma **120** of FIG. 1A-1 to bridge the main cathode to anode gap and initiate a breakdown **122** of FIG. 1A-2 across the main cathode to anode gap. The arc breakdown is across a plasma bridge whose resistance is <50 m Ω , allowing higher currents to flow from **C1** through **L1** and the arc discharge. The much higher resistance of the trigger path ensures that negligible current flows through the trigger electrode path, as shown by trigger current plot **804** which returns to zero at ~55 μ s as the anode arc current increases. Furthermore, the blocking capacitor **C2 210** offers increasingly higher impedance as the current increases, going from <1 Ω for the 100 ns rise-time of the switch voltage up to >6000 Ω during the slower period of the main arc. Hence the trigger path is active only for on the order of 10 μ s after the switch **208** is opened. The trigger electronic current **804** goes negative at 50 μ s of FIG. 8 when the main plasma arc from cathode to anode ignites, since the blocking capacitor **C2 210** now drives current in the reverse direction through the arc. The switch **208** voltage drops to about 33 V after about 53 μ s, which is the arc burning voltage (sheath drop+Ohmic drop across the arc resistance). In this example, the voltage reaches a peak of about 400 V before decaying back to the arc burning voltage of about 33 V.

FIG. 9 shows the result when the trigger interval **T1** is too short, or not enough voltage is developed at the trigger electrode to initiate a plasma. As the voltage developed by discontinuously interrupting the inductor current is LdI/dt , care must be taken not to exceed the breakdown voltage of switch **208**. This protection is provided by overvoltage device **209**, which may be any device which clamps a voltage which exceeds a threshold and has sufficiently fast response time to provide protection to the switch during transient voltage events. One such device is a metal oxide Varistor (MOV) **209**. In the example waveforms of FIG. 9, switch voltage **904** reaching 1200 V with weak or delayed plasma formation results in the MOV **209** shunting some of the current as shown in waveform **902**, thereby protecting the switch **208** from overvoltage breakdown. This protection device's **209** clamp voltage is selected for prevention of overvoltage damage to switch **208**. Inductor current **906** is also shown for reference.

The various charging times, plasma arc discharge times, cycle times, and circuitry are shown for example purposes only, and many other variations are possible. The plasma arc was described as being activated in discrete thrust events using discrete energy level stored in an inductor. Alternatively, a DC voltage source may be placed between anode electrode and cathode electrode, such that when the initiator electrode develops a plasma arc, the DC source maintains the plasma arc in steady state until the DC source is removed. In a discrete pulsed mode, the energy storage capacity of the energy storage capacitor is:

$$\frac{CV^2}{2}$$

12

where **C** is the capacitance and **V** is the energy storage capacitor. In addition, the capacitance, plasma electrode geometry, spacing and Ohmic resistance govern the interval of time for which the arc is maintained, and the durations and waveforms given are illustrative in nature for the components used, and are not intended to limit the values of these components or waveform durations and times they produce. In one example of the invention, the initiation (micro-gap sparks) lasts on the order of 1 μ s, and the plasma thrust (plasma current flowing between cathode and anode) is on the order of 1 ms or on the order of 5 ms.

Example shapes of insulator surfaces of region **301** of axial trigger FIG. 3 are shown in detail FIG. 3A, and example circumferential insulator surfaces of region **401** of FIG. 4 are shown in detail FIG. 4A. The shape of these surfaces to maintain a thin coating of plasma-forming metal are critical for the long-term operation of the plasma thruster. As shown in an example insulator of FIG. 3A region **301**, by stepping the insulator **101** surface to create a planar insulator surface **304** and proximal surfaces **305** and **306** below the cathode face **302**, the surface resistance of the depressed segment of the insulator **306** may be kept nearly constant over many plasma cycles and extend the longevity of the thruster. One specific function of the shape of the insulator **101** geometry is to provide one or more surfaces of the insulator which are obscured from re-deposition of metal ejected from the face of the cathode **108/113**. Example proximal surfaces **305** or **306** of FIG. 3A may perform this function. The surface of the insulator **101** may rely on an initial metallization or deposition such as graphite particles on the order of 1 μ thickness with micro-gaps between particles to form multiple diffuse areas where micro-arcs may form in the small gaps of the surface metallization, which are critical to the initiation of the plasma arc. An insulator surface resistance in the range of tens of ohms to thousands of ohms is preferred, although other resistances may be used which form microplasmas in the gaps between surface metallization. Other insulator surface profiles are shown in the insulator detail FIG. 3B, showing a ramp with obscured surface **314** adjacent to a deposition surface **312**, FIG. 3C showing a sawtooth with obscured surface **320** and exposed surface **318**, or alternative of FIG. 3C-1 which shows a sawtooth with peaks **321** providing a gradient of material removal/deposition between the two surfaces (one fully obscured and one partially obscured) on either side of peak **321**. FIG. 3D shows a ramped insulator **326**, which may be used with a trigger electrode **110** which has a surface **330** flush with depressed region of insulator **101**, or the trigger electrode **110** may extend to full height flush to the cathode **108** as shown with profile **328**. Additionally, the trigger electrode profile may be flat, as shown, or tapered to a point (not shown), beveled to a flat surface **328** (not shown), or rounded (not shown). FIGS. 3E, 3F, and 3G show additional embodiments of insulator **101**, with surfaces **318**, **324**, **328/330**, respectively, which are obscured from redeposition of plasma ejected from the cathode by geometry with respect to returning plasma metal ions. In cases where the incidence of re-deposition is low, a flat surface **331** of FIG. 3H may be used. Insulator **101** may have any shape which provides an equilibrium for vaporization and redeposition of cathode material, in one example, where at least one surface is obscured from redeposition, or in another example, providing equilibrium between erosion from plasma trigger events, and re-deposition from returning metal ions after the trigger events. Insulator **101** may have other non-planar surface features such as rippled surface features which provide an equilibrium of metal deposition

and ejection from each plasma thrust event, or the insulator 101 may have a roughened surface which preserves micro-plasma formation in the microgaps on the metallization. The design constraint for the insulator may be stated thus: the thickness of new material deposited on each pulse over obscured surfaces such as 305 and 306 of FIG. 3A (or the obscured surfaces of the other exemplar insulators of FIGS. 3B-3H), in total, should be equal to the thickness that is eroded by each trigger flashover thrust event. In one example of the invention, the depth of 306 relative to surface 304 and width of the groove forming surfaces 305 and 306 is selected to have an aspect ratio of 2 or more, and the equilibrium of deposition/erosion is applied to at least one of surface 305 or 306. The aspect ratio of the features is understood to be the depth of the feature parallel to the cathode central axis divided by the width of the feature parallel to the face of the cathode. When this balance is achieved, the insulator 101 acts as a reliable trigger with a repeatable surface resistance over millions of pulses. For example, in a 5 kg orbit raising example described later in this application, the total number of pulses for a 14 days mission at 2 Hz is 2.5×10^6 . The total propellant mass burned in this period is approximately 30 g. A single Molybdenum (Mo) cathode in the MPT 30 mm in diameter would erode this mass over a depth of 4 mm. Insulator 301 is shown in detail FIG. 3A. Over successive plasma discharge events, metal ions from cathode 108 tend to accumulate on insulating interface 304. This accumulation may reduce the surface resistance for the trigger current. A groove 306 obscures proximal regions of the insulator from metal ion re-deposition. The depth of groove is selected such that the material which is removed by a plasma ignition event is equal to the re-deposition of new material from a main plasma arc event. In this manner, the re-deposition of material offsets the material lost, and the igniter remains usable over millions of ignition events. FIG. 4A of the circumferential trigger geometry shows a similar groove formed by surfaces 406 and 406 which are shielded from re-deposition of ions released from cathode 113, whereas surface 404 is expected to receive depositions more heavily than surfaces 406 or 407. The insulator configurations for an axial trigger electrode of FIG. 3 may be utilized in the circumferential trigger geometry of FIG. 4 by mirroring the insulator feature so that a surface profile which was near a central trigger electrode is maintained when the trigger electrode is circumferential. For example, the insulator profile of FIG. 3A (with stepped surface 306 adjacent to the trigger electrode 110) may be mirrored to transform to the insulator profile shown in FIG. 4A (which maintains the stepped surface 406 adjacent to the trigger electrode 109). Similarly, the insulator 101 features 414, 417, and 416 of circumferential trigger FIG. 4B may be transformed from the corresponding insulator 101 features 312, 314, and 316, respectively, of axial trigger FIG. 3B by mirroring the surface features. Accordingly, the insulator profiles shown in the figure sequence 3C to 3H may be similarly transformed for circumferential trigger use, as shown in the figure sequence 4C to 4I, respectively thereby maintaining at least one proximal surface which is obscured from re-deposition of plasma ions ejected from the cathode. The insulator 101/111 material need not be a high temperature ceramic, as the insulator surface is exposed to a small fraction of the trigger plasma briefly during part of T1, and T1 is a small fraction of the plasma duration T1+T2. A suitable insulator 101/111 is one which supports on the order of 1 μ of surface

metal deposition and has a melting temperature sufficient to withstand the energy imparted from the trigger arc over repeated cycles.

In one example of the invention, the MPT has a diameter 5 in the range of 5 mm to 40 mm. In another example of the invention, with reference to FIG. 2, the MPTs are arranged over one or more surfaces of a cube of approximate dimension 10 cm $\times$ 10 cm $\times$ 10 cm, one or more surfaces of the cube having a plurality of MPTs, each MPT including an anode 10 lead 106 which includes a capacitor C2 210 to the respective MPT trigger, and the cathode leads 104 commonly connected. For this configuration, a single power supply 201 may be used for a cube face to control a particular orthogonal thrust direction, each MPT (or a group of MPTs) on a 10 particular surface connected via a switch element (reed relay 15 or other low resistance switch), with one group of MPTs at a time connected, and the others isolated. In this manner, one or more MPTs may be selected until its useful lifetime of 20 thrust pulses is exhausted, after which the MPT with associated capacitor 210 may be isolated, and a new MPT and associated capacitor 210 selected for continued operation.

FIGS. 10A, 10B, and 10C show a dual trigger geometry metal plasma thruster which provides an extended usability life for the cathode through a dual trigger with differential 25 actuation depth range. A central inner trigger electrode 1008 is surrounded by an inner insulator 1010, which may have any insulator geometry for a coaxial insulator as was described in FIGS. 3A to 3H. The surfaces 1040 and 1044 of the inner insulator 1010 which are not in contact with the 30 inner trigger electrode 1008 are treated with a conductive surface providing micro-gaps such as a surface graphite treatment for initiating the plasma by providing micro-gaps for arc formation. The metal cathode 1006 outer surfaces are covered by outer insulator 1004 which has an extent of 35 conductive surface such as surface 1044 graphite on an inner surface and a outer surface shorter extent 1020 for contact with the outer trigger electrode 1002. The arrows 1024 and 1022 indicate the initial plasma initiation event of FIGS. 1A-1 and 1B-1, respectively, and the thicker arrows 1023 40 indicate the plasma thrust event which follows and was shown in FIGS. 1A-2 and 1B-2. FIG. 10A shows the initial state of the metal plasma thruster with 100% cathode propellant over an extent from terminus 1015 to cathode face extent 1017. For this first stage of cathode propellant 45 shown in FIG. 10A, the outer trigger electrode 1002 may be driven by itself, or the outer trigger electrode 1002 may be driven in conjunction with inner trigger electrode 1008, or the inner trigger 1008 and outer trigger 1002 may alternate or be driven in an arbitrary order as is required to provide uniform depletion of the cathode 1006 during successive 50 thrust events.

In one example of the invention shown in FIGS. 10A, 10B, and 10C, the inner insulator 1010 has a partially or 55 fully conductive surface treatment 1040 creating microgaps over an extent from the cathode opposite the cathode face to a range such as 30% to 60% of original cathode extent L3, shown as L1 1011, where the original cathode extent from start of cathode 1015 to cathode face is shown as L3 1013. As the cathode 1006 erodes, the cathode extent reduces to 60 L4 2019 shown in FIG. 10B and finally to L5 2019 shown in FIG. 10C. The inner insulator 1010 has a conductive or partially conductive surface treatment 1040 providing microgaps over extent L2 1012 from terminus 1015 to less than cathode original extent L3 1013, and the outer insulator 65 1004 has a conductive or partially conductive surface treatment 1044 over extent L1 1011 from original cathode face 1017 to less than an extent to terminus 1015. As the cathode

1006 extent shortens from **L3 1013** of FIG. **10A** to **L4 1019** of FIG. **10B**, the initiation arc path on the surface of outer insulator **1004** grows, whereas the initiation arc path of inner insulator **1010** remains unchanged. Eventually, the arc path length **1044** becomes too long to reliably initiate the plasma, and the surface treatment **1040** of inner insulator **1010** dominates for plasma initiation from the life of the cathode from extent **L4 1019** of FIG. **10B** to **1021** of the propellant end of life (EOL) shown in FIG. **10C**.

FIG. **10D** shows a detail region **1030** of insulator **1004** and electrode **1002** from FIG. **10A**. A microgap imitating surface may comprise graphite particles **1032** deposited onto outer insulator **1004**, which are over-coated with cathode re-deposition **1034** of metal such as Mo from previous plasma thrust events. FIG. **10D** shows an initiation phase where sparking at the microgaps of the surface coating **1032** cause microplasma **1038** to form, which creates an electrical pathway for the full plasma discharge of the thrust phase shown in FIG. **10E**. An initiation event of FIG. **10D** may last on the order of a micro-second, whereas the thrust event of FIG. **10E** lasts on the order of milliseconds.

The axial trigger mechanism of FIG. **3** and circumferential trigger mechanism of FIG. **4** may be extended to rectangular or square geometries as shown in FIG. **11** for the square plasma thruster comprising four trigger electrodes **1102A**, **1102B**, **1102C**, and **1102D**, outer insulator **1104** with microgap conductive surface for initiating the plasma, and cathode **1106**. FIG. **11A** shows a cross section view of FIG. **11A** and includes the porous anode **114**, which is shown in a first embodiment without inner trigger electrode **1120** or inner insulator **1124**, and in another example of the invention, the added elements of inner trigger electrode **1120** and inner insulator **1124** shown in FIG. **11B** for the detail **1120** of FIG. **11** may be used. FIG. **11D** shows the corresponding cross section view of the inner trigger electrode **1120** and inner insulator **1124**, which has a surface coated with a conductive material forming micro-gaps as before. In another variation of the invention, the inner trigger electrode **1120** and inner insulator **1124** may be used alone for triggering, and the plasma thruster does not have the outer insulator **1104** and outer trigger electrodes **1102A**, **1102B**, **1102C**, and **1102D**. The geometry of FIG. **11A** is preferable for full surface utilization when used with the thruster cube **1200** of FIG. **12**. In one example of the invention of FIG. **11**, square or rectangular cathode **1106** of FIG. **11** may initiate using a single trigger electrode or any combination of trigger electrodes **1102A**, **1102B**, **1102C**, and **1102D**. In another variation of the invention shown in detail **1120**, an inner trigger electrode **1122** and inner insulator **1124** are used without the surrounding outer trigger electrodes **1102A**, **1102B**, **1102C**, and **1102D**.

FIGS. **10A**, **10B**, **10C**, **10D**, and **10E** are understood to be applicable to a circular or square cathode geometry without limitation. Additionally, in one example of the invention, the outer trigger electrode **1002** may be formed as two or more isolated conductors so that separate triggering of the plasma across the face of the cathode may be performed by individually actuating the trigger electrode segments, as was described for FIG. **11**.

FIG. **12** shows an example 3 axis thrust control cube, where five of the six external surfaces have thrusters attached to provide orthogonal thrust directions. In the example of FIG. **12**, each surface of the thrust cube **1200** has four thrusters mounted in an orthogonal arrangement, with bottom thrusters **1206** providing **+Z** thrust, top thrusters **1202** providing **-Z** thrust, left side thrusters **1204** providing **+X** thrust, and right side thrusters **1210** providing **-X** thrust.

Front thrusters **1210** provide **+Y** thrust. In a typical configuration for a satellite thruster, each opposite surface of the satellite would have a thrust cube, which would have a surface configured to provide an opposing **-Y** thrust. In a typical satellite deployment, 2 to 8 or more such thrusters of FIG. **12** may be employed. Each surface may have an arbitrary number of thrusters, which may be activated individually or in groups to provide granularity of thrust events with orthogonal direction. By mounting a 3 axis thrust cube **1200** at equal offset and orientation about a center of mass of a satellite, control of rotational velocity and static position with respect to the center of mass may be achieved by initially firing thrusters in opposite directions on opposing sides to begin a rotation, and then firing opposite thrusters to stop the rotation. As is well known in satellite thruster prior art, discrete thrust events such as those generated by the plasma thrusters positioned on thrust control cube **1200** may be used for precise positioning and orientation of the satellite, as well as moving the satellite from one orbital position to another.

FIG. **13** shows a schematic diagram of an example three axis thruster for use with the thrust cube of FIG. **10**. Power supply **1301** is operative as was described in FIG. **2**, where a DC supply **1302** charges energy storage capacitor **1308 C1**, as before. Capacitor **C1** may be two 21 mF capacitors in parallel. As described for FIG. **2**, trigger switch **1310** closes for a duration of time sufficient to maximize an instantaneous current in **L1 1306**, after which switch **1310** releases, allowing the current stored in inductor **L1 1306** to be directed to one or more selected thrusters in thruster cube assembly **1318**. Trigger switch **1310** may be formed using four IGBT devices, and storage inductor **L1 1306** can be a 70 uH inductor, thereby providing 150 A rising roughly linearly in 320 us. Blocking capacitor **1330** can be a value such as 500 nF which couples the trigger voltage to a selected trigger electrode through a trigger switch such as insulated gate bipolar transistor (IGBT) **1326**. The selection of individual thrusters is accomplished using thruster select inputs **1332**, which are coupled to isolating drivers **1328**, which may be optoisolators or other isolating switch elements which allow for low voltage control and isolation from the large magnitude transient voltages of the actuated thrusters of **1318**. Each driver such as **1328** is coupled to a trigger switch **1326** which may be an IGBT **1326**, which is either in an ON state or OFF state. For the case of an IGBT switch **1326** in the ON state, the instantaneous current is coupled through blocking capacitor **1330** and applied to the collector (drain) electrode of the trigger switches such as **1334**, which in the ON state is coupled to the emitter (source) **1336**, which couples the associated trigger current to the trigger electrode of thruster **1324**, which initiates a triggering plasma from the cathode to the trigger electrode, which plasma initiates the main arc discharge from the cathode electrode of **1324** to anode electrode **1320**, generating thrust as was previously described. Each driver of the trigger driver **1316** is configured so that each individual thruster **1338** through **1322** are individually selectable for a thrust generation event. As was previously described, the duration of the plasma provided by the circuit of FIG. **13** is primarily governed by the energy storage device **1306** and thruster electrode geometry, and may be within the range of orders of magnitude greater than 6 us or orders of magnitude less than 6 us.

In an alternative embodiment of the invention as was previously described for providing continuous plasma thrust, a switchable DC source may be applied across the anode **1312** and cathode **1314** electrodes of FIG. **13**, and

selected thrusters initiated with a voltage pulse to the initiator electrode (replacing capacitor 1330) sufficient to initiate the plasma in selected thrusters, where the plasma is continuously operative until the switchable DC source is removed.

The individual thruster geometry used in the thruster cube 1318 is shown as the circumferential trigger geometry for thrusters 1338 through 1322 of FIG. 13, including any of the configurations shown in FIG. 1B, 4, 4A, or 4B. Example circumferential trigger thruster 1338 is shown with outer trigger electrode 1342, inner cathode electrode 1342, and insulator 1346. Thrusters 1338 through 1322 can alternatively be any of the axial geometries previously described for FIG. 1A, 1B, 3, 3A, 3B, 3C, 3D, 3E, 3F, or 3D, 4, 4A, 4B, 4C, 4D, 4E, 4F, 4G, 4H, 4I, 10A, 10B, 10C, or 11A. For the variations of FIG. 11, with or without inner trigger and inner insulator or outer trigger and outer insulator, any of the insulator profiles shown in the FIG. 3 series and FIG. 4 series may be used for the shape of the inner insulator or outer insulator to ensure equilibrium between deposited and evaporated cathode material during plasma thrust events.

Additionally, the thrusters 1338 to 1322 of thruster cube 1318 may be placed on a single surface or multiple surfaces of the cube of FIG. 10 with any number of thrusters on a particular surface. In certain configurations of a satellite, there may be an orbital direction vector, for which thrust which is not symmetric with respect to a line of action (or travel) may induce an angular moment to the satellite, causing undesirable rotation. To counter this, it may be preferable to place symmetric pairs of thrusters on a particular surface and to actuate the thrusters in pairs, one on either side of the line of action, to prevent a rotational moment in the delivered force. These are example configurations given for understanding of the invention and are not intended to limit the scope of the invention.

In one example of the invention, each of the thrusters on a surface of the thruster cube are configured to be connected to the anode 1312 and cathode 1314 conductors of the power supply 1301 and each thruster is individually selectable using thruster input 1332 which selects the particular thrusters to receive a trigger pulse to produce thrust, whereas the non-selected thrusters which do not receive the trigger pulse remain passive. In this manner, granularity of pulsed plasma from one or more orthogonal surfaces is possible. In one example of the invention, the pulsed power supply 1301 and trigger driver 1316 are packaged in an inner enclosure of FIG. 10 which has thrusters of 1318 on outer surfaces as shown in FIG. 10, thereby providing low loss coupling from inductor 1306 to selected thrusters of thruster cube 1318.

Many such configurations are possible, this particular example is given for illustration only.

Compared to the VAT device, the MPT differs from the prior art VAT in three distinct ways:

- (4) the MPT has plasma arc currents in the range of -200 A to 300 A or more vs. the VAT which has currents of ~100 A, which reflect the characteristic of the underlying energy storage elements: inductors (with higher Ohmic loss) result in lower currents than capacitors (with lower Ohmic loss).
- (5) The MPT arc has a longer duration (~3 ms to 12 ms) compared to the arc duration in a VAT (~100 µs to 500 µs), due to the use of capacitors as storage elements.
- (6) The inductor in an MPT for initiating the plasma is on the order of 20 pH-80 pH vs. 1 mH for a VAT which stores the plasma energy in the inductor. The inductor in the MPT stores <2% of the energy delivered to the arc on each cycle.

The higher values of ISP offered by the MPT make it more fuel efficient than the PPT for missions in space. It is well known from the rocket equation that for a given mission in orbit, the amount of propellant that must be exhausted from the spacecraft at a given exit speed depends strongly (exponentially) upon this exit speed. The propellant mass M_p is related to the initial spacecraft mass M_o by:

$$M_p = M_o \left(1 - e^{-\frac{\Delta V}{u_e}}\right) \quad (1)$$

where ΔV is the velocity change required for the orbital maneuver and u_e is the exhaust speed of the propellant. Eq. 1 shows that for a given maneuver, the higher the exhaust speed, the lower the mass of propellant that is required.

For example, consider the example of raising a spacecraft from an orbit of 500 km above the earth to a higher orbit of 700 km. These orbits place the spacecraft well above the 411 km orbit of the International Space Station (ISS) and hence avoid cluttering that orbit and potentially posing a threat to manned missions. The equations of orbital mechanics may be used to calculate the change in velocity (defined as ΔV) required to accomplish such an orbital maneuver, which is 110 m/s. Table 2 lists three different types of propulsion: (1) The Metal Plasma Thruster that is the subject of the present invention with Molybdenum as a candidate propellant; (2) a pulsed plasma thruster (PPT) sold by Busek corporation; (3) a FEEP Thruster sold by ACCION.

TABLE 2

RAISE A 5 kg nano-SAT FROM 500-700 KM ORBIT				
	Mo MPT	Busek PPT	ACCION FEEP	
speed	17235	5258	17658	m/s
ΔV	110	110	110	m/s
M_o	5	5	5	kg
M_p	32	104	31	g

Assuming that each of these thrusters is used to raise a 5 kg spacecraft (such as a nano-satellite) from an orbit of 500 km to 700 km (this maneuver requires a ΔV of 110 m/s), the propellant mass M_p required by each of these engines is calculated from Eq. 1 and given in the last row of the table. The Mo MPT and ACCION FEEP both require about 30 g to be burned, while the Teflon® (PTFE) PPT requires about 100 g. The advantage of higher ISP of the MPT and the FEEP is lower propellant mass required.

The thrust efficiency of any of the electric propulsion systems is determined primarily by the energy cost to create the ion from the solid (Teflon® PPT or MPT) or liquid (FEEP) state. The FEEP is the most efficient of all three systems since the field evaporation is a direct, non-thermal extraction by quantum tunneling across a potential barrier. The Teflon® PPT and the MPT both use a thermal process to ionize the atoms. In such a thermal process the ionization cost is much higher, approximately 100 eV per atom vs. approximately 10 eV per atom in the FEEP. As a result, thrust/power input ratio of the FEEP is higher than that of the Teflon® PPT or the MPT. But the mass of the MPT (for a given power) is much lower than that of the FEEP. Hence the thrust/mass ratio of the MPT and FEEP are comparable.

The examples shown in the present invention are intended for understanding the invention, which may be practiced in many different ways. It is understood that the example values for the inductor, first capacitor, second capacitor,

voltages and currents, trigger electrode to cathode electrode, insulator gap and insulator surface profile and shape are typical examples, rather than limitations of the invention, which is established by the claims which follow. Quantities which are referenced within an order of magnitude are understood to be a factor of 10, or more, larger or smaller than the referenced quantity. In an example variation, the trigger current is periodically measured and used to change the threshold voltage for starting the thrust cycle adaptively to higher or lower voltage levels. In this manner, the detection of additional metal deposition on the surface of the insulator (from an increased V/I peak at arc initiation) would result in a change in threshold voltage to increase the erosion rate, and the detection of increased metal erosion (from a decreased V/I peak at arc initiation) would result in a change in threshold voltage in the opposite direction. The direction of controller threshold adjustment to higher or lower voltages may be performed adaptively based on measurement, or based on an electrode wear, pulse discharge count, or other algorithm.

I claim:

1. A metal plasma thruster comprising:
a porous anode;
an inner trigger electrode;
an inner insulator surrounding the inner trigger electrode 25
and having a first conductive coating, the first conductive coating having micro-gaps, wherein the first conductive coating is in contact with the inner trigger electrode;
a metal cathode surrounding the inner insulator, the metal cathode having a first extent;
an outer insulator surrounding the metal cathode, the outer insulator having a second conductive coating, the second conductive coating having additional micro-gaps; 30
an outer trigger electrode in contact with the second conductive coating;
the metal cathode having a terminus and a face exposed to the porous anode;
the inner insulator having a second extent from the 40 terminus which is less than the first extent;
the second conductive coating having a third extent starting from the face which is less than the first extent.
2. The metal plasma thruster of claim 1 where the metal cathode comprises an alloy or element including at least one of: Magnesium (Mg), Aluminum (Al), Radium (Ra), Barium (Ba), Strontium (Sr), Cerium (Ce), Europium (Eu), Ytterbium (Yb), Calcium (Ca), Lanthanum (La), Praseodymium (Pr), Silver (Ag), Neodymium (Nd), Actinium (Ac), Gold (Au), Samarium (Sm), Copper (Cu), Promethium (Pm), Uranium (U), Manganese (Mn), Beryllium (Be), Gadolinium (Gd), Terbium (Tb), Dysprosium (Dy), Nickel (Ni), Holmium (Ho), Cobalt (Co), Erbium (Er), Yttrium (Y), Iron (Fe), Scandium (Sc), Thulium (Tm), Palladium (Pd), Protactinium (Pa), Lutetium (Lu), Titanium (Ti), Thorium (Th), Platinum (Pt), Zirconium (Zr), Chromium (Cr), Vanadium (V), Rhodium (Rh), Hafnium (Hf), Technetium (Tc), Ruthenium (Ru), Iridium (Ir), Niobium (Nb), Molybdenum (Mo), Tantalum (Ta), Osmium (Os), Rhenium (Re), Tungsten (W), Carbon (C), Francium (Fr), Cesium (Cs), Gallium (Ga), Rubidium (Rb), Potassium (K), Sodium (Na), Indium (In), Lithium (Li), Tin (Sn), Polonium (Po), Bismuth (Bi), Thallium (Tl), Cadmium (Cd), Lead (Pb), and Zinc (Zn).
3. The metal plasma thruster of claim 1 where at least one of the first conductive coating or the second conductive coating comprises graphite.

4. The metal plasma thruster of claim 1 where the face of the metal cathode is square or rectangular.
5. The metal plasma thruster of claim 1 where the outer trigger electrode is square or rectangular.
6. The metal plasma thruster of claim 5 where the outer trigger electrode comprises a plurality of conductive segments.
7. The metal plasma thruster of claim 6 where at least one of the conductive segments of the plurality of conductive segments comprises a linear edge parallel to an edge of the metal cathode.
8. The metal plasma thruster of claim 1 where the face of the metal cathode is circular.
9. The metal plasma thruster of claim 1 where an electrical discharge which forms in the micro-gaps or the additional micro-gaps initiates a plasma which forms between the metal cathode and the porous anode.
10. The metal plasma thruster of claim 1 where at least one of said inner insulator or said outer insulator is formed from at least one of: a ceramic, alumina, glass or an epoxy laminate.
11. A metal plasma thruster comprising:
a porous anode;
a central cathode, the central cathode having an exposed face directed toward the porous anode, wherein the exposed face is square or rectangular and comprises a plurality of edges;
an outer insulator in contact with at least one edge among the plurality of edges, the outer insulator having a first conductive surface with micro-gaps;
an outer trigger electrode having a second conductive surface in contact with the outer insulator;
wherein the outer insulator is configured to initiate a plasma between the central cathode and the porous anode.
12. The metal plasma thruster of claim 11 where the central cathode further comprises an inner insulator enclosing an inner trigger electrode.
13. The metal plasma thruster of claim 11 where the central cathode comprises an alloy or element including at least one of: Magnesium (Mg), Aluminum (Al), Radium (Ra), Barium (Ba), Strontium (Sr), Cerium (Ce), Europium (Eu), Ytterbium (Yb), Calcium (Ca), Lanthanum (La), Praseodymium (Pr), Silver (Ag), Neodymium (Nd), Actinium (Ac), Gold (Au), Samarium (Sm), Copper (Cu), Promethium (Pm), Uranium (U), Manganese (Mn), Beryllium (Be), Gadolinium (Gd), Terbium (Tb), Dysprosium (Dy), Nickel (Ni), Holmium (Ho), Cobalt (Co), Erbium (Er), Yttrium (Y), Iron (Fe), Scandium (Sc), Thulium (Tm), Palladium (Pd), Protactinium (Pa), Lutetium (Lu), Titanium (Ti), Thorium (Th), Platinum (Pt), Zirconium (Zr), Chromium (Cr), Vanadium (V), Rhodium (Rh), Hafnium (Hf), Technetium (Tc), Ruthenium (Ru), Iridium (Ir), Niobium (Nb), Molybdenum (Mo), Tantalum (Ta), Osmium (Os), Rhenium (Re), Tungsten (W), Carbon (C), Francium (Fr), Cesium (Cs), Gallium (Ga), Rubidium (Rb), Potassium (K), Sodium (Na), Indium (In), Lithium (Li), Tin (Sn), Polonium (Po), Bismuth (Bi), Thallium (Tl), Cadmium (Cd), Lead (Pb), and Zinc (Zn).
14. The metal plasma thruster of claim 12 where at least one of one of said inner insulator or said outer insulator is formed from at least one of: a ceramic, alumina, glass or an epoxy laminate.
15. The metal plasma thruster of claim 14 where the epoxy laminate is FR4.
